UNITED STATES PATENT OFFICE.

THOMAS EVANS ASKEW, OF ST. PAUL, MINNESOTA.

CAR-COUPING.

SPECIFICATION forming part of Letters Patent No. 450,129, dated April 14, 1891.

Application filed August 29, 1890. Serial No. 363,462. (No model.)

To all whom it may concern:

Be it known that I, THOMAS EVANS ASKEW, of St. Paul, in the county of Ramsey and State of Minnesota, have invented certain new and useful Improvements in Car-Couplings; and I do hereby declare the following to be a full, clear, and exact description of the same, reference being had to the accompanying drawings, forming a part of this specification, 10 and to the figures of reference marked thereon.

This invention relates to improvements in car-couplings, particularly of the class commonly known as link-and-pin couplings, and has for its object to provide a means where- 15 by the link and pin may be held in coupling position without the necessity of the attendant's remaining between the cars during the coupling operation; to which end it consists in certain novel details of construction to be 20 hereinafter described, and pointed out particu- larily in the claims at the end of this specification.

Referring to the accompanying drawings, Figure 1 is a side elevation of a pair of draw- 25 heads having my invention applied thereto. Fig. 2 is a longitudinal vertical section of the same. Fig. 3 is a face view of one of the coupling-heads, and Fig. 4 is a cross-section through the other coupling-head.

30 Similar numerals of reference in the several figures indicate the same parts.

In the drawings, 8 and 9 represent two co-operating draw-heads, each having the usual chambers therein for the reception of the 35 ends of the link 3, and apertures for the passage of the coupling-pins 2. In the head 8, and preferably at a point slightly in rear of the coupling-pin, is pivoted a pin-support 4, having a socket or seat 10 for the pin in its 40 upper portion and adapted to swing approximately from the position shown in full lines, Fig. 2, to that shown in dotted lines, Fig. 1. Within the chamber in the head 8 the pin-support is provided with a projection extend- 45 ing below its center of oscillation and adapted when struck by the link to throw the support forward for a purpose which will pres- ently appear.

In the co-operating draw-head is journaled 50 a shaft 5 at approximately the same relative

position as the pivot of the pin-support, which shaft is provided with a projection 6 within the draw-head adapted to bear on the upper surface of the link when inserted in the head and regulate the elevation of its front end. 55 Outside of the head, the shaft is provided with a ratchet-wheel 12, with which co-operates a pawl 13 for holding the shaft and link in proper position and in order to enable the train-man to give the outer end of the link 60 the proper elevation without going between the cars. The shaft 5 is extended and provided at the outer ends with handles 11, as will be readily understood by referring to Figs. 1 and 4. 65

The operation is as follows: Assuming that the two cars to be coupled are approaching each other, the train-man first throws the pin-support over and rests the pin in its seat therein, as shown in dotted lines, Fig. 1, with 70 the end resting in the pin-hole. He then inserts the link in the co-operating head beneath the link-support and inserts the pin in that head. Then, if the draw-heads are of known height with relation to each other, he 75 may turn the shaft 5 until the front end of the link is at the proper elevation and lock the same in this position by means of the pawl and ratchet-wheels 12 and 13; or if the relative height of the heads be not known 80 he may grasp one of the handles 11 and as the cars approach guide the link properly into the co-operating head. As the link enters this head it comes in contact with the projection 7 and throws the upper portion of 85 the pin-support forward, causing the pin to assume an upright position and instantly drop into place through the link.

From this description it will be seen that I have provided an exceedingly simple and 90 efficacious coupling mechanism capable of being manipulated even by inexperienced persons, and which may be applied to the common link-and-pin couplings now in every-day use at a minimum cost. 95

Having thus described my invention, what I claim as new is—

1. In a car-coupling, the combination, with the co-operating draw-head, link, and pin, as described, of the link-support consisting of 100

the substantially horizontal shaft having the projection 6 thereon, the handle 11, and the ratchet and pawl 12 and 13, as set forth.

2. In a car-coupling, the combination, with 5 the co-operating draw-heads, link, and pins, as described, of the pin-support pivoted in one draw-head, with the upward extension having the pin-seat in which the pin is adapted to rest at an angle, and the downward extension, 10 with which the link is adapted to engage, and

the link-support in the co-operating draw-head, consisting of the shaft 5, projection 6, and handle 11, substantially as described.

In testimony whereof I have hereunto set my hand in presence of two subscribing witnesses. 15

THOMAS EVANS ASKEW.
